UNITED STATES PATENT OFFICE.

LAVERN EDWARD MOORE, OF PALO ALTO, CALIFORNIA.

CALENDAR FOR PENCILS.

Application filed January 15, 1925. Serial No. 2,652.

To all whom it may concern:

Be it known that I, LAVERN EDWARD MOORE, a citizen of the United States, residing at Palo Alto, in the county of Santa Clara and State of California, have invented 5 certain new and useful Improvements in Calendars for Pencils; and I do hereby declare the following to be a full, clear, and exact description of the invention, such as 10 will enable others skilled in the art to which it appertains to make and use the same.

This invention relates to a calendar for pencils, other writing instruments or the like.

15 It is aimed to provide a novel construction which is inexpensive, simple and durable, which may be used perpetually and which may have its securing nut function as a clip to attach a pencil or the like to the 20 clothing of the wearer.

The specific objects and advantages will become apparent from a consideration of the description following taken in connection with accompanying drawing illustrating 25 an operative embodiment.

In said drawing:

Figure 1 is a view in side elevation illustrating the device in place on a pencil;

Figure 2 is a vertical sectional view on the 30 line 2—2 of Figure 1; and

Figures 3, 4 and 5, are perspective views of the cylinder, the day ring and the fastening clip, respectively.

35 Referring specifically to the drawing wherein like reference characters designate like or similar parts, the device uses a cylinder as at 10 which may be of metal or other suitable material and be applied to a pencil 11 by engaging the same friction tight or by 40 being positively fastened thereto in any desired manner. The device may equally as well be attached to a pen or another equivalent article as will be readily understood.

45 The upper part of the cylinder from its periphery is cut away in order to provide shoulders as at 12 and 13. Between the shoulders 12 and 13 a cylindrical portion 14 of reduced diameter is afforded and above the shoulder 13, a further reduced portion

15 is provided which is exteriorly screw 50 threaded.

The lower portion of the cylinder 10 is sub-divided into seven vertical rows 15^a of equal width and containing numerals to represent the days within a month. 55

Resting on the shoulder 12 and fitted about the portion 14 is a "day" ring 16 which has vertical rows or divisions of the same width as those at 15^a and in which the days of the week are delineated in full or abbreviated as shown. The ring 16 is turnable on the part 14 so that the days of the week may be brought into registry with any of the columns 15 according to the occurrence 60 of the days in the different months which thus makes the calendar perpetual. In order that the ring 16 may be retained in its adjusted position, it has depending lugs as at 17 adapted to enter notches as at 18 65 in the shoulder 12. 70

The ring 16 cannot become accidentally displaced since a fastening or securing nut in the form of a ring 18^a is screw threaded to the portion 15 and bears on the shoulder 13. When the securing nut 18 is in the latter position, the ring 16 cannot move vertically and thus the notches 17 cannot become accidentally disengaged from those at 18; hence in order to adjust the ring 16, it is necessary to first loosen the nut 18 slightly, then adjust the ring 16 and thereafter tighten the nut 18. This nut 18 has a spring 75 clip or tongue 19 extending therefrom so that it may clip onto a pocket or other portion of the clothing of the wearer in the same 80 manner as an ordinary clip. 85

Various changes may be resorted to provided they fall within the spirit and scope of the invention.

What is claimed is:—

90 1. A calendar device of the class described having a cylinder provided with delineations representing the days of a month, a ring coating therewith and adjustable relatively thereto having designations of the 95 days of the week thereon, and means to secure said ring in place and the device to the clothing of the user.

2. A calendar of the class described having a cylinder provided with a first reduced portion and with a second reduced portion, the second reduced portion being screw threaded, a shoulder at the junction of the first reduced portion and remainder of the cylinder, a shoulder at the junction of the two reduced portions, notches in the first mentioned shoulder, a ring adjustable on the

first mentioned reduced portion having projections to enter said notches, coacting calendar delineations on said ring and cylinder, and a securing element for the ring screw threaded to the second mentioned reduced portion.
